UNITED STATES PATENT OFFICE.

GEORGE W. HULSHIZER, OF STEWARTSVILLE, NEW JERSEY, ASSIGNOR TO INGERSOLL-RAND COMPANY, OF JERSEY CITY, NEW JERSEY, A CORPORATION OF NEW JERSEY.

AIR-FEED BRAKE.

Application filed September 16, 1925. Serial No. 56,648.

To all whom it may concern:

Be it known that I, GEORGE W. HULSHIZER, a citizen of the United States, and a resident of Stewartsville, in the county of Warren and State of New Jersey, have invented a certain Air-Feed Brake, of which the following is a specification, accompanied by drawings.

This invention relates to rock drills, but 10 more particularly to an air feed brake for fluid actuated rock drills of the stoper type.

The objects of the invention are to equip the feeding element of a rock drill with a brake adapted to be applied by pressure fluid 15 acting against the feeding piston for preventing recoil of the rock drill at the time the hammer piston strikes the drill steel, to enable such brake to be automatically released upon the release of pressure fluid from 20 the feeding cylinder and to increase the drilling efficiency of rock drills of the stoper type.

Further objects will be in part obvious and in part pointed out hereinafter.

25 The invention consists of the combinations of elements, features of construction and arrangement of parts having the general mode of operation substantially as herein-after described and more particularly pointed out in the appended claims and illustrated 30 in the accompanying drawings, in which—

Figure 1 is a longitudinal view in elevation and partly in section of a rock drill 35 constructed in accordance with the practice of the invention, and

Figure 2 is a longitudinal detail view in elevation partly in section showing the manner in which the air feed brake is applied.

40 Referring to the drawings, a preferred modification of the invention is shown embodied in a rock drill of the stoper type having a cylinder A and a front head B secured to the cylinder by means of cushioned 45 side bolts C. A drill steel D is inserted into the front head B to receive the blows of a hammer piston (not shown) reciprocating within the cylinder A. A back head E forms a closure for the rear end of the cylinder

50 A and has secured thereto a rotation handle F whereby the drill may be manually rotated for keeping the drill steel D free within the drill hole.

To the end that the drill may be advanced 55 toward the work as the drill steel D pene-

trates the rock G, a feeding cylinder H having a flange J is secured to the cylinder A by means of bolts K. The bolts K also serve to clamp the back head E between the cylinders A and H and thus hold the cylinders 60 and the back head in operative position. A piston rod L is arranged within the cylinder H and carries at its outer end a rock engaging pointer O which supports the drill and holds the drill in position.

In accordance with the practice of the invention, a conical extension P is formed on the inner end of the piston rod L and has a reduced cylindrical extension Q which engages slidably a piston R whereby the inner 70 end of said rod is held concentrically within the cylinder H. The piston R in this instance has a bore S, a portion of which is cone shaped to correspond with the conical extension P so that the piston may move freely longitudinally of said extension, a spring T abutting at one end the conical extension P and at its other end a shoulder U of the piston R tends to constantly force 75 said piston away from the extension P.

80 Means are provided for preventing recoil of the drill from the working face at the time the hammer piston strikes the drill steel, to this end an annular groove V is 85 formed in the piston R to receive a frictional member or members W preferably in the form of fibre segments shaped to conform at their outer surface with the bore of the cylinder H. A plurality of radial holes X are formed in the piston R to receive plungers Y arranged slidably therein to abut with 90 one end the segments W and with the opposite end the conical extension P.

The piston R in this instance has a reduced extension Z to permit a sealing member 95 in the form of a cup leather b to be arranged thereabout for the purpose of preventing leakage of pressure fluid between the piston R and the cylinder H. A collar c is arranged above the extension Z of the 100 piston to bear at one end upon the said cup leather b and is held firmly in position by means of a nut d screwed on the end of said extension.

To the end that the feeding element may 105 be properly centralized with the back head E, a feeding cylinder bushing e is arranged in the inner end of the cylinder H to extend into the back head E and has a bore f through which pressure fluid may pass into 110

the cylinder H for causing longitudinal movement between said cylinder and the piston R. In addition to serving as a passage for pressure fluid therethrough, the 5 bore f also serves as a means for frictionally engaging a split spring ring g carried by a nut h on the end of the cylindrical extension Q of the piston rod L. In this way the piston rod L may be securely held 10 against endwise movement while the drill is being transported.

Pressure fluid for operating the drill is admitted through a suitable connection j into the back head E and the admission 15 thereof into the percussive and feeding elements is controlled by a suitable throttle valve (not shown) having a throttle lever k.

In order to provide for the release of pressure fluid from the feeding cylinder H in 20 case the drill steel D becomes stuck in the drill hole, or if for other well known reasons it be desired to retard the feeding speed of the drill, the rotation handle F is provided with a longitudinal passage o which 25 communicates with the cylinder H through a passage p in the back head E, said passage p being in communication with the bore of the cylinder H. Suitable controlling means preferably such as are disclosed in 30 the U. S. Patent No. 1,407,591 granted February 21, 1922 to F. M. Slater for an air feed control for rock drills, may be employed for controlling the passage o. Accordingly, a valve q is arranged transversely 35 through the passage o and is so positioned with respect to the grip portion of the handle that said valve may be conveniently manipulated by the operator.

In the operation of the device, assuming 40 that the drill is in operation and that the valve lever k is therefore in the correct position for simultaneously admitting pressure fluid to the percussive and feeding elements, pressure fluid entering into the feeding cylinder H will advance the drill in accordance with the penetration of the drill steel into the rock, and acting against the piston R will force said piston outwardly or downwardly along the extension Q. Such 45 pressure against the piston will compress the spring T and cause the plungers Y to force the fibre ring or segments W against the wall of the cylinder H and serve as a brake to prevent recoil of the percussive element at the time the hammer piston of the drill strikes the drill steel. If, for well known reasons, it be desired to withdraw the drill somewhat from the work, pressure 50 fluid from the feeding cylinder H may be released by proper manipulation of the valve q. Upon such release of pressure fluid the spring T will automatically raise the

piston R and thus move the plungers Y out of contact with the conical extension P and release the pressure against the segments W. 65 Similarly, if it be desired to cease drilling operations the pressure fluid to the percussive and feeding elements may be shut off, and by bleeding the air from the feeding cylinder the braking action of the segments 70 W will be automatically released by the spring T as herein described. The drill, together with the cylinder H, may then be lowered until the spring ring g is forced into the bore f of the bushing e. Owing 75 to the expansibility of the spring ring g sufficient friction will be obtained between the said ring and the bore f to hold the piston, together with the piston rod, against 80 endwise movement while the drill is being transported.

By this construction the undesirable feature of recoil in drills of this type is entirely eliminated; and due to the automatic release of the braking device a free advance 85 of the drill towards the working face is at all times assured.

I claim:

1. In an air feed brake for a fluid actuated rock drill, the combination of a feeding cylinder with a fluid actuated piston, a rod for said piston and slideable longitudinally with respect thereto, a conical extension on said rod, frictional members in said piston, and radially extending plungers slideable in the piston to abut at one end the conical extension and to abut at the other end the frictional members to force said members outwardly against the cylinder and prevent recoil of the cylinder during the operation 100 of the drill when pressure fluid acts against the piston.

2. In an air feed brake for a fluid actuated rock drill, the combination of a feeding cylinder with a fluid actuated piston, a rod for said piston and slideable longitudinally with respect thereto, a conical extension on said rod, fibre segments in said piston, radially extending plungers slideable in the piston to abut at one end the conical extension and to abut at the other end the fibre segments to force said segments outwardly against the cylinder and prevent recoil of the cylinder during the operation of the drill when pressure fluid acts against the piston, and a spring for automatically moving the piston longitudinally in one direction with respect to the rod to release the fibre segments upon the release of pressure fluid from the cylinder.

In testimony whereof I have signed this specification.

GEORGE W. HULSHIZER.
